FIG. 5.

FIG. 1 is a perspective view of a clock radio showing the clock side of my new design;

FIG. 2 is a front elevational view thereof;

FIG. 3 is a right-side elevational view thereof;

FIG. 4 is an elevational view of the radio side thereof; and

FIG. 5 is an enlarged perspective view of the clock side of the design, swiveled on its base 90° from the position shown in FIG. 1.

The dominant features of the invention reside in those portions shown by means of full lines in the drawing.

I claim:

The ornamental design for a clock radio, substantially as shown and described.
